UNITED STATES PATENT OFFICE.

PHILIP R. STANHOPE, OF DENVER, COLORADO.

ORE-CRUSHING STAMP-MILL.

1,026,717.

Specification of Letters Patent.

Patented May 21, 1912.

Application filed August 12, 1911. Serial No. 643,744.

To all whom it may concern:

Be it known that I, PHILIP R. STANHOPE, a citizen of the United States of America, residing in the city and county of Denver 5 and State of Colorado, have invented a new and useful Ore-Crushing Stamp-Mill, of which the following is a specification.

My invention relates to improvements in ore crushing stamp mills, and the objects of 10 my invention are: First. To provide a portable, easily constructed, inexpensive ore crushing stamp mill that can be easily and quickly erected in out-of-the-way and practically inaccessible places, for the general 15 types of ore crushing machinery in general use. Second. To provide an ore crushing mill, parts of which can be made of raw materials generally found where the mill is to be erected. I attain these objects by the 20 mechanism illustrated in the accompanying drawings, in which:

Figure 1 is a side elevation of a stamp mill embodying my invention, the screen, which is supported upon the mortar block, being 25 in section. Fig. 2 is a plan view of the same. Fig. 3 is a perspective view of the stamp showing the same secured to the forward end of the lever or beam by which it is 30 operated. Fig. 4 is a transverse sectional view of the stamp beam, showing a roller carrying stirrup thereon, to which is attached a spring for exerting a down pull on the stamp beam. Fig. 5 is a side view of 35 the improved hopper screen, and Fig. 6 is a plan view of the screen frame or hopper, the screen bars being removed.

Similar reference numerals refer to similar parts throughout the several views.

Referring to the drawings: The numeral 40 1 designates the mortar block for the ore crusher. This mortar block may be constructed of any suitable material; my invention, however, contemplates its manufacture of concrete from gravel, sand and 45 broken rock abounding in the vicinity of the site of the mill, leaving only the cement to be transported into the mountains to the mill site. This mortar block is provided with a step 2, which surrounds it, and which 50 is located close to the top of the block. Upon the top of the block is placed an iron plate 3, which is provided with a rectangular 55 recess or depression of slight depth, in which is seated a die 4, the plate 3, being held stationary upon the top of the block

by the smaller end of a hopper screen, which is constructed as follows:

The screen comprises upper and lower rectangular frames 5 and 6, respectively, which are connected either by boards or by 60 sheet metal to form a hopper, three sides of which are provided with rectangular openings 7, substantially of the width of the lower end of the hopper. If desired, however, these openings may be formed in any 65 one, or in all of the sides of the hopper. The lower frame 6, of the hopper, rests upon the step 2, as shown in Fig. 1, and by surrounding the plate 3, on all sides, prevents sliding movement of the same. In line with the 70 openings 7, the frames 5 and 6, are each provided with a series of V-shaped grooves or recesses 8, in which are placed steel bars 9, which are triangular in cross-section, the sides being of equal width, and these bars 75 constitute the screen proper. The flat sides of these screen bars lie inward, and the spaces between their adjoining edges determine the mesh of the screen; the spaces being increased or diminished in width, 80 by varying the distance between the V-shaped grooves 8, as will be understood. The screen bars are held in place by strips 10, of either wood or metal, which are screwed to the inside faces of the frames 85 5 and 6, against the upper and lower ends of the said bars, as shown in the drawings. By this arrangement, the bars may be quickly secured and when the edges of any of the bars become worn, or jagged from the impact of the ore as it is in process of crushing, the said bars may be withdrawn and turned to bring a fresh edge in place, without removing the retaining strips 10. 90

The upper and lower hopper frames 5 and 6, support the V-shaped screen bars with one of their flat sides inward and one of their edges outward, which arrangement provides a large clearance area between the screen bars beyond their adjoining edges. The bars may be adjusted to give a discharge of ore pulp between their adjoining edges, of as fine a mesh as desired. The shape of these bars enables them to be turned so that each edge can be used until 100 worn away, and they can also be turned end for end.

A feed chute 11 is arranged to feed ore into the hopper screen onto the die.

A stamp 12 is employed, which may also 110

be of any suitable material, such as steel castings, or chrome, or other suitable steel. The stamp is provided on its upper face with a dove-tailed projection 14, which fits 5 into a corresponding slot 15, in the under side of a block 16, which is also provided upon its upper side with a corresponding dove-tailed slot 17, in which one end of a beam or lever 18 is secured; this lever 18 10 preferably comprises a plank of any wood such as hickory having an inherent springing property, and its end which fits into the dove-tailed recess of the stamp is beveled to fit the dove-tailed recess tightly, but is arranged to be driven further through the stamp block as its forward end wears away 15 or becomes splintered from the vibratory action of long use. This plank is adapted to exert a downward resilient pressure that 20 will enable it to strike an effective ore crushing blow when raised and released by a cam 19, such as is commonly used in stamp mill practice. To accomplish this I secure the opposite end of this plank in a substantially 25 fixed position by a yoke clip 20, to a support comprising a cross beam 21, which is supported on upright beams or posts 22. This end of the plank is arranged to extend through and beyond the clip 20 a short distance 30 to permit the plank to be moved forward as its stamp end wears away.

Intermediate of the support 21 and the mortar block 1, and adjacent to said mortar block, I secure suitable foundation or supporting blocks 22^a, upon which bearings 23 are secured, in which a shaft 24 is mounted. On this shaft is mounted a double ended cam or tappet 19, in such relative position to the under side of the plank that it will 35 bear on a wearing plate 26, which is secured to the underside of the plank and raise the plank and allow the stamp block at its end to drop as the ends of the tappet escape the plate, as is well understood. A driving pulley 27, is also secured on the shaft 24 and is connected by a belt 28, with a power driven shaft—not shown—by which the pulley, with its shaft and tappet, are rotated and the stamp beam raised. 45

In order to supplement the gravity action 50 of the stamp 12 and block 16, together with springing action of the stamp beam or plank, in accomplishing the quick drop of the stamp, I provide a yoke or stirrup 29, between the ends of which is mounted a roller 30, which rests upon the top of the stamp beam. To the depending end of this yoke is secured one end of a coil spring 31, of sufficient stiffness to exert the required pull upon the beam. The other end of this spring is secured to an eye bolt 32, which is secured in any suitable fixed object, such as a floor beam, or a block embedded in the ground. Thus as the ends of the tappet alternately release the stamp beam it will 55 be drawn violently downward by the combined action of gravity and of the spring 31, causing the stamp to deliver in quick succession, sharp, resilient, blows upon the ore as it feeds in upon the die. 60

While I have shown the faces of the die and stamp on a horizontal plane, they may be inclined slightly toward the front side of the screen if desired. It will be understood that the stamp is designed to be used 75 in connection with any preferred style of screen other than that illustrated in the drawings.

Having described the invention, what I claim and desire to secure by Letters Patent, is:

In a stamp mill as specified, the combination with a support, of a resilient beam secured at one end to the support; a stirrup having a roller mounted therein, which rests upon said beam between its ends; a coil spring for exerting a down pull upon said stirrup; a stamp on the free end of the beam; a mortar operatively positioned relatively to the stamp; and a cam between the stamp and stirrup for raising and releasing the stamp end of the beam. 85 90

In testimony whereof I affix my signature in presence of two witnesses.

PHILIP R. STANHOPE.
